TEXTILE WINDING MACHINES

Jeffrey O'Neill Fisher, Dainebury, Goldcroft Common, Caerleon, and Eric Wilson, Stevenage, England, assignors to British Nylon Spinners Limited, Pontypool, England

Filed Sept. 11, 1959, Ser. No. 839,362
2 Claims. (Cl. 242—26.3)

The present invention relates to textile winding machines such as down-twisting and like machines, for winding double taper yarn packages.

Conventional textile downtwisters and the like known hitherto have not been capable of providing a high rate of throughput combined with a low lay ratio. As explained below, such a combination necessitates a very high traverse speed, and it is the object of the present invention to produce this combination.

The expression downtwisters and like machines is defined as including downtwisters, doublers, and similar machines wherein the yarn proceeds in a downward direction to the spindle where it is wound up, such as the draw-twisting apparatus claimed in British patent specification No. 543,466, which is designed for drawing synthetic linear polymers e.g. polyamides.

After yarn consisting of such a synthetic linear polymer, for instance, polyhexamethylene adipamide, has been wound on to a bobbin or tube so as to form a package and is allowed to remain for a time on the said package, in accordance with the requirements of textile usage, the yarn gradually tends to contract somewhat. This tendency to contract has the effect of producing an increased tension or strain in the yarn. In the case of a tapered package this change is not uniform, but is found to be accentuated in those parts of the yarn which occupy the tapered portion or portions of the package, supposedly because the yarn in these regions tends to have less resilient yarn beneath it to act as a cushion and permit contraction, than the yarn elsewhere. Be this as it may, however, and the invention is in no way dependent on the correctness of the theory outlined above, the fact remains that when such yarn is removed from the tapered package and woven into a fabric, undesirable light and dark bars or stripes are often observable in the weft. These stripes are visible both before and after dyeing and are known as the barré effect.

Now the lower the lay ratio employed in winding, the closer together are the above-mentioned stripes. Moreover, by bringing the stripes close enough together, it has been shown experimentally that they can thus be masked or made unnoticeable so that they no longer detract from the appearance of the woven fabric.

The lay ratio, sometimes defined as the number of coils of yarn per inch of package measured along the axis of the bobbin, is proportional to the throughput of yarn divided by the traverse frequency. For a given degree of inserted twist, the lay ratio becomes proportional to the speed of the bobbin spindle divided by the traverse frequency. The lay ratio can be reduced therefore by decreasing the bobbin speed and/or increasing the traverse frequency. But it would be economically undesirable to decrease the bobbin speed because this is tantamount to reducing the throughput, i.e. lowering the output. A remedy for barré was accordingly sought in an increased traverse frequency. Modern winding machinery designed for synthetic yarn is however accurately made and capable of a high speed of running, for instance, a spindle speed of 7,500 revolutions per minute corresponding, for a certain degree of twist, to a throughput of 1,500 feet per minute. In order therefore to achieve a sufficiently low lay ratio to mask the barré

2

effect, relatively high traverse speeds are required, namely, of the order of 50-100 cycles per minute. Such traverse speeds have not hitherto been practically attainable but it has now been found that winding at this range of speed can be accomplished by means of the following machine, the subject of the present invention. In this way it is accordingly possible to wind yarn consisting of synthetic linear polymers, e.g. a polyamide such as polyhexamethylene adipamide, without the fault of barré being noticeable in fabric woven from the said yarn.

The following table illustrates the relationship between old rayon winding machines (A), modern winding machines for synthetic yarn (B) and the present winding machines (C). The figures quoted are necessarily very inexact because naturally the speeds employed vary so considerably. It is however clear that the speed of the traverse of the present machines has not been practically obtainable before. The lay ratio has been calculated in the following way:

20 Definition of lay ratio; number of coils per inch of package.

Circumference of package; assumed to be 3".

Length of stroke of traverse (i.e. half cycle); assumed to be 4".

25 The lay ratio is then given by the expression,

$$\left(\frac{\text{Throughput in feet per minute}}{\text{Cycles of traverse per minute}} \right) \times \frac{12}{3} \times \frac{1}{4 \times 2}$$

30	Machine	Spindle, r.p.m.	Throughput feet per min.	Cycles per Minute	Feet per cycle	Lay ratio
	A-----	1,500	250	5	50	25
35	B-----	7,500	1,500	5	300	150
	C-----	7,500	1,500	50-100	30-15	15-7½

The invention relates to textile winding machines, which comprise in combination a spindle adapted to wind yarn packages, a traverse mechanism therefor, a 40 rotary motor with crank to convey, by means of conventional connecting means, a reciprocatory motion, corresponding approximately to a simple harmonic motion, to said traverse mechanism, the rotary motor itself being movably mounted so as to be capable of reciprocating in the direction of the aforesaid reciprocatory motion, a servomechanism for causing the said rotary motor to reciprocate in accordance with the contour of a cam, the follower of which actuates the servomechanism, so that the reciprocatory motion due to the rotary motor is superposed on the reciprocatory motion due to the cam, the contour of which latter is designed so that the traverse mechanism produces a double taper yarn package.

The present machines enjoy the advantages of a simple and robust construction. Since the motion of the 55 traverse is nearly simple harmonic, or, in other words, since the time/displacement curve represents approximately a sine wave, the absence of shock to the mechanism is ensured.

The rotary motor may be driven by compressed air, or 60 electricity but a hydraulic motor is preferred, that is, a motor driven by a liquid under pressure.

The employment of the servomechanism has the advantage that the cam follower needs only to support a very small load. Consequently no roller is needed, and the 65 follower can be sharp so as to follow the contour of the cam accurately.

The invention includes a process for winding yarn consisting of synthetic linear polyamides by means of a winding machine comprising in combination a spindle adapted to wind yarn packages, a traverse mechanism therefor, a rotary motor with crank to convey, by means of conventional connecting means, a reciprocatory motion, cor-

responding approximately to a simple harmonic motion, to said traverse mechanism, the rotary motor itself being moveably mounted so as to be capable of reciprocating in the direction of the aforesaid reciprocatory motion, a servomechanism for causing the said rotary motor to reciprocate in accordance with the contour of a cam, the follower of which actuates the servomechanism, so that the reciprocatory motion due to the rotary motor is superposed on the reciprocatory motion due to the cam, the contour of which latter is designed so that the traverse mechanism produces a double taper yarn package, wherein the rotary motor rotates at 50-100 revolutions per minute. As already stated it is preferred that the said rotary motor be hydraulic.

The shape or contour of the double taper packages obtained by the present winding machines is controlled, for a given setting of the machine (e.g. length of traverse stroke, distance of reciprocation of rotary motor) by the shape of the cam employed.

For the purpose of illustrating but not limiting the invention the following embodiment thereof is described with reference to the accompanying diagrammatic drawings.

In FIGURE 1 there is depicted in elevation a textile winding machine which is a downtwister, 1, is the spindle, 2 the double taper yarn package, 3 the ring rail attached to the reciprocating vertical rod 4, which constitute the traverse mechanism, 5 is the rotary motor, 6 the crank conveying a reciprocatory motion to rod 4 by the connecting means which comprise the reciprocating rod 7, the links 8, 9 and the bell crank 10. The rotary motor is moveably mounted on the flanged wheels 11, which run on the track 12.

FIGURE 2 illustrates the downtwister in plan and is numbered similarly. In FIGURE 2 is also shown, on a somewhat larger scale for the sake of clarity, the servomechanism reversal valve 13, the cordate cam 14 and the connecting links therefor 15, 16, 17, 18. 19 is the knife edge which follows the contour of the cam 14.

The mode of operation of the machine is as follows. The rotary motor is driven hydraulically and serves to impart an approximately simple harmonic reciprocatory motion to the rod 4, and thence to the ring rail 3, by means of the rod 7 and the crank 10 with the links 8 and 9. In this connection it is to be noted that the links 8 and 9 are of equal length and the arms of the crank 10 are also equal in length. Moreover if perpendiculars be drawn from the pivot of the crank 10 to the rod 7 and to the rod 4 produced as shown by the dotted lines, then these perpendiculars are equal in length. It may be added that it is not necessary for the arms of crank 10 and the links 8 and 9 to be respectively equal, but if the links 8 and 9 are not equal then the respective arms of the crank 10 must be in the same ratio to each other as are the links immediately connected to these arms. For example, if the link 9 is twice the length of the link 8, then the arm of the crank 10 connected to the link 9 must be twice the length of the other arm of crank 10.

The rotary motor 5 itself is moved upon the rails 12 by means of a conventional hydraulic ram H which is controlled by the reversal valve 13 so that, starting from the neutral position shown in the drawing in which the rams would be stationary, a small movement of the rod 20 from left to right sets the ram in motion, so as to move the motor 5 along its rails from right to left. Similarly, a small movement of the rod 20 from right to left would cause the motor 5 to be moved from left to right. Now rod 20 is pivoted to the centre point of the link 16, which in turn is connected via link 17 to link 18 which latter is fixedly pivoted to plate 21. At the centre of link 17 is mounted a knife edge which is urged resiliently (by a spring not shown) against the cam 14. The link 17 is twice the length of the link 15. Assuming for the moment, that the rotary motor 5 (although in rotation) is stationary upon its rails 12, and that the reversal valve

13 is, as shown in FIGURE 2, in its neutral position. Now if the cam 14 revolve a little so that the knife edge follower 19 moves from left to right, the link 16 will be pushed to the right, pivoting at link 15, and pushing rod 20 from left to right. But this latter motion of rod 20, as already explained above, will have the effect of moving the motor 5 along its rails from right to left. This motion will push the upper end of link 16 (as drawn) from right to left, and likewise move rod 20 from right to left until the reversal valve returns to its neutral position, when the motor 5 ceases to move along its rails. Similarly, if the cam 14 push the knife edge follower 19 from right to left, the motor 5 will be moved along its rails from left to right until the reversal valve again returns to its neutral position. In this way by means of the servomechanism comprising the reversal valve 13 and the ram the motor 5 is made to move along its rails in accordance with the motion of the cam follower 19 as the cam 14 revolves, because the valve 13 always tends to remain at its neutral position. The point 22 where rods 16 and 20 are pivoted will accordingly in practice not move. Since the pivot at 21 is a fixed point and link 18 equal to the lower half (as drawn) of link 16, it can be deduced that the knife edge 19 will move along a nearly straight line (shown dotted) which is at right angles to the line (also shown dotted) which joins the pivots 21 and 22. It is remarked that the cam 14 is so disposed that the straight line along which the knife edge 19 moves passes, when produced or extended, through the centre of the cam 23.

As an example of the operating conditions of the above downtwister the following data are quoted:

Yarn—polyhexamethylene adipamide yarn of 20 filaments of 3 denier each;

35 Bobbin—1 1/4" diameter tube;

Speed of spindle—7,500 revolutions per minute;

Rate of yarn wind-up—1,500 feet per minute;

Rate of rotary motor—80 cycles per minute;

Traverse stroke—4";

40 Distance of reciprocation of rotary motor—4";

Rate of cam—15 minutes per revolution.

The shape or profile of the cam in the present embodiment of the invention corresponds to the following polar coordinates which extend from 0°-180°. Since the cam is symmetrical the radii from 180°-360° are identical but in the reverse order.

	Angle of rotation	Cam radius in inches	Angle of rotation	Cam radius in inches
55	0.00	4.00	86.91	3.00
	0.85	3.95	94.24	2.95
	2.12	3.90	101.57	2.90
	3.76	3.85	108.90	2.85
	5.76	3.80	116.23	2.80
	8.12	3.75	123.56	2.75
	10.82	3.70	130.13	2.70
	13.84	3.65	136.11	2.65
	17.19	3.60	141.55	2.60
	20.87	3.55	146.56	2.55
60	24.92	2.50	151.20	2.50
	29.24	3.45	155.49	2.45
	33.90	3.40	159.49	2.40
	38.98	3.35	163.17	2.35
	44.55	3.30	166.53	2.30
	50.67	3.25	169.60	2.25
	57.59	3.20	172.35	2.20
	64.92	3.15	174.78	2.15
	72.25	3.10	176.87	2.10
	79.58	3.05	178.58	2.05
65			180.00	2.00

What we claim is:

1. In a textile winding machine for winding a double taper yarn package comprising a spindle, means for rotating the spindle to wind yarn, a yarn guide for distributing yarn along the spindle and means for reciprocating the guide along the spindle in approximately simple harmonic motion; the improvement in which said reciprocating means comprises a rotary motor, crank means connecting the motor to said yarn guide to reciprocate said guide

when said motor turns, means mounting said motor for reciprocating motion, a cam, means for rotating said cam, follower means in operative relationship with said cam, and a servomechanism for reciprocating said motor in response to the movement of said follower, when said cam rotates.

2. Textile winding machine as claimed in claim 1, wherein the rotary motor is a hydraulic motor.
